UNITED STATES PATENT OFFICE

2,039,862

VACUUM CLEANER

Noble H. Watts, Bridgeport, Conn., assignor to
 General Electric Company, a corporation of
 New York

Application October 18, 1933, Serial No. 694,094

6 Claims. (Cl. 15—16)

The present invention relates to electric vacuum cleaners of the portable household type and has for its object to provide an improved construction and arrangement of supporting wheels 5 for such cleaners whereby the suction nozzle may be adjusted readily and conveniently and whereby there is provided a simple, compact, neat appearing construction capable of being manufactured at low cost and not likely to get out of order. 10 For a consideration of what I believe to be novel and my invention, attention is directed to the accompanying description and the claims appended thereto.

In the drawing, Fig. 1 is a perspective view of 15 an electric vacuum cleaner provided with wheel supporting and adjusting means embodying the invention, and Fig. 2 is a detailed perspective view in section illustrating the mechanism.

Referring to the drawing, 1 indicates the casing of a vacuum cleaner, 2 indicates the nozzle, 3 20 indicates the handle and 4 indicates the dust bag. The cleaner casing is supported by two front wheels 5 located just back of the suction nozzle (only one of which shows in the drawing) and by two rear wheels 6 located under a rear extension 7 which forms a part of the cleaner casing. With this arrangement, it will be seen that by raising and lowering the rear wheels, the casing will be turned on the front wheels as a fulcrum to raise and lower the suction nozzle relatively 25 to the floor. The present invention relates particularly to an improved arrangement for raising and lowering the rear wheels.

In the side walls of extension 7 are two vertically extending holes 8 in which are located slideable tubular sleeves 9. Wheels 6 are pivoted in yokes 10 to which are attached posts 11 (this being a usual castor construction) which fit into sleeves 9 so that the posts may swivel therein.

On the upper ends of sleeves 9 are circular racks comprising teeth 12 which mesh with pinions 13 fixed by set screws 14 to a shaft 15 pivotally mounted in bearings 16 in opposite side walls of extension 7. By providing circular racks 45 on the sleeves 9, the sleeves may rotate in the openings 8 to assist the casters in maintaining the wheels in alignment and the pinions 13 will be kept in continuous mesh with the racks. The outer sides of pinions 13 engage the ends of bearings 16, thus serving to hold shaft 15 against transverse movement but permitting it to turn freely in its bearings.

For turning shaft 15, there is provided a lever 17 which at one end is fixed to the shaft, the other 55 end projecting out through a slot 18 in the top

wall 19 of extension 7 and being provided with a handle 20. Slot 18 extends down through the rear wall of extension 7 also, so as to provide for ample adjustment. This brings the handle out to a point on top of the cleaner casing where it is readily accessible and convenient to reach.

For holding shaft 15 in any adjusted position, a segment 21 having pointed teeth 22 on its edge is fastened on the shaft by a set screw 23, and is adapted to be engaged by a roller 24 carried by a 10 yoke 25 on the rear end of a lever arm 26. The forward end of lever arm 26 is provided with a sleeve 27 pivotally mounted on a shaft 28 carried by the side walls of extension 7. On the top of yoke 25 is a short guide pin 29 which projects 15 into a vertical opening 30 in the top wall 19 of extension 7 and engaging the pin is a spring 31 located in opening 30 and held under compression by an adjustable threaded plug 32. Spring 31 holds roller 24 in engagement with teeth 22. 20

For balancing, or partially balancing the upward thrust of sleeves 9 on pinions 13, due to the weight of the cleaner, there is provided a coiled spring 33 which surrounds shaft 15 with one end hooked around a pin 34 in the shaft and the other 25 end engaging a wall 35 which forms a part of extension 7. Spring 33 is under suitable tension in a direction such that it tends to oppose turning of shaft 15 due to the weight of the cleaner resting on wheels 6. In other words, spring 33 30 acting on shaft 15 tending to turn it in one direction serves to balance the weight of cleaner body which tends to turn shaft 15 in the other direction. This means that shaft 15 is held from turning primarily by spring pressed roller 24 35 and that when lever 17 is turned in a direction either to raise or lower wheels 6, it is necessary only to overcome the pressure of spring 31 so as to cause roller 24 to ride over the sloping sides of teeth 22.

The discharge tube 36 to which dust bag 4 is connected communicates with a passage 37 in the lower portion of extension 7 which passage is formed by walls of extension 7. Passage 37 and tube 36 are located centrally at the rear of the 45 cleaner casing and it will be noted that openings 8 are formed one on each side of passage 37 while the adjusting mechanism is located in extension 7 above such passage. This construction gives a compact symmetrical arrangement and 50 one wherein the parts are enclosed.

To adjust the wheels, it is necessary merely to move lever 17 to turn shaft 15 and pinions 13, the pinions acting on the racks to move sleeves 9 and the wheels. When shaft 15 turns, seg-

ment 21 turns with it, riding under roller 24, notch by notch. The handle, itself, serves as an indication of the adjustment of the wheels and, since the movement of the handle is through a 5 relatively large arc, accurate adjustment is readily made. If desired, marks may be provided on the casing adjacent to the slot 18 to indicate correct wheel adjustments.

What I claim as new and desire to obtain by 10 Letters Patent of the United States, is:

1. In a vacuum cleaner, a casing having walls forming a discharge conduit at its rear and having spaced side walls on opposite sides of the discharge conduit extending above the discharge 15 conduit, means connecting said discharge conduit and said side walls whereby said discharge conduit reinforces said side walls, vertically arranged passages between the side walls on opposite sides of the discharge conduit, members slidably 20 mounted in said passages, wheels carried by the lower ends of said members, the upper ends of said members being provided with teeth, a shaft mounted transversely in said side walls, means including pinions on the shaft between said side 25 walls for meshing with the teeth on said members, and a lever projecting beyond the confines of said side walls for turning said pinions.
2. In a vacuum cleaner, a casing having spaced vertical rear walls with circular openings there- 30 in having vertical axes, adjustable members in said openings, wheels carried by said members, a transverse shaft in said walls, a lever connected to said shaft and projecting through a wall of the casing for turning the shaft, pinions 35 mounted on the shaft, and circular racks on the said members with which the pinions mesh.
3. In a vacuum cleaner, a casing including a hollow rear extension having spaced side walls, walls extending between the top and rear edges 40 of the side walls, a discharge conduit between and at the lower ends of the side walls, means connecting said discharge conduit and said side walls whereby said discharge conduit reinforces said side walls, supporting wheels below said rear 45 extension, and means within the confines of the walls of said extension and outside said discharge conduit for adjusting the vertical position of said wheels.

4. In a vacuum cleaner, a casing including a hollow rear extension having spaced side walls, walls extending between the top and rear edges of the side walls, a discharge conduit between and at the lower ends of the side walls, means 5 connecting said discharge conduit and said side walls whereby said discharge conduit reinforces said side walls, supporting wheels below said rear extension, means including a rotatable shaft within the confines of the walls of said extension and outside said discharge conduit for adjusting the vertical position of said wheels, and means including a lever projecting beyond the confines of the walls of said extension for rotating said shaft.

5. In a vacuum cleaner, a casing including a hollow rear extension having spaced side walls, walls extending between the top and rear edges of the side walls, means including a discharge conduit between the side walls for forming the 20 bottom wall of the extension, supporting wheels below the rear extension, and means within the confines of the walls of said extension and outside said discharge conduit for adjusting the vertical position of said wheels.

6. In a vacuum cleaner, a casing including a hollow rear extension having spaced side walls, walls extending between the top and rear edges of the side walls, a discharge conduit between and at the lower ends of said side walls, means 30 connecting said discharge conduit and said side walls whereby said discharge conduit reinforces said side walls, vertically arranged passages between the side walls of said extension and on opposite sides of the discharge conduit, members 35 slidably mounted in said passages, wheels carried by the lower ends of said members, the upper ends of said members being provided with teeth, a shaft mounted transversely in said side walls and outside said discharge conduit, means including pinions on the shaft between said side 40 walls for meshing with the teeth on said members, and a lever projecting beyond the confines of the walls of said extension for turning said pinions.

NOBLE H. WATTS.
